UNITED STATES PATENT OFFICE.

AUGUST MAGNAN, OF GREAT FALLS, MONTANA.

WRENCH.

1,348,832.

Specification of Letters Patent.

Patented Aug. 3, 1920.

Application filed August 11, 1919. Serial No. 316,630.

To all whom it may concern:

Be it known that I, AUGUST MAGNAN, a subject of the King of Italy, residing at Great Falls, in the county of Cascade and 5 State of Montana, have invented certain new and useful Improvements in Wrenches; and I do declare the following to be a full, clear, and exact description of the invention, such as will enable others skilled in the art 10 to which it appertains to make and use the same.

This invention relates generally to tools, and more particularly to wrenches.

The principal object of the invention is to 15 provide a wrench by which broken pipe may be easily removed from unions, elbows or other couplings, the wrench being provided with jaw faces which engage the interior wall of the pipe or the like and hence do not injure the threads in any way.

Another object of the invention is to provide a wrench of this character which may be adjusted to accommodate different sizes of pipes or the like, and has an efficient 25 means for effecting a tight gripping engagement of the jaws with the pipe.

A further object of the invention is to generally improve upon devices of this class by the provision of a comparatively simple, 30 strong, durable and inexpensive construction, one which will be efficient and reliable in operation, and well adapted to the purpose for which it is designed.

With these and other objects in view, the 35 invention consists of certain novel features of construction and the combination and arrangement of parts as will be hereinafter fully described and claimed.

In the accompanying drawings in which 40 similar reference characters designate like parts throughout the several views:—

Figure 1 is a side elevation of a wrench constructed in accordance with this invention;

Fig. 2 is a view of one edge of the wrench; Fig. 3 is a view of the other edge thereof; and,

Figs. 4 and 5 are transverse sectional views taken on the planes indicated by the lines 45 4—4 and 5—5 of Fig. 1.

Referring more particularly to the drawings, the numeral 1 designates an L-shaped member having a long shank 2 and a short shank 3, the former forming the handle of 50 the wrench while the latter forms the fixed

jaw. The free end of the short shank 3 is provided with an opening 4, and slideable through this is the long shank 5 of another L-shaped member 6, said long shank being arranged in a substantially parallel relation 60 with the long shank 2 of the member 1. The short shank 7 of the member 6 is substantially parallel with the short shank 3 of the member 1 but it extends in the opposite direction from said shank 3 so as to overlie the 65 same.

The numeral 8 designates an L-shaped lever, the short arm 9 of which is provided with an opening 10 to receive the shanks 2 and 5 of the members 1 and 6 and is pivoted 70 by means of a bolt 11 to the long shank 2 of the member 1. The long arm of the lever extends alongside of the shank 2 and in connection with the latter forms the handle of the wrench, the arm 12 being capable of being 75 pressed against the shank 2 to swing the arm 9 upwardly.

The long shank 5 of the member 6 is substantially rectangular in cross section and the opening 4 in the shank 3 of the member 80 1 and the opening 10 in the short arm of the lever 8 is shaped more or less to conform to the shape of the shank 5 so as to prevent the latter from turning in these openings. The edges of the shank 5 are threaded as at 85 13 to receive a nut 14 disposed between the lower side of the shank 3 of the member 1 and a washer 15 resting upon the upper side of the short arm 9 of the lever 8. The washer 15 has a substantially rectangular 90 shaped opening 16 through which the shank 5 passes, and whereby said washer is prevented from rotating. By turning the nut 14 the L-shaped member 6 will be moved longitudinally with respect to the L-shaped 95 member 1 so that the distance between the short shanks of these members or in fact the jaws of the wrench will be moved farther apart or closer together.

The outward movement of the longitudinal arm 12 of the lever 8 is limited by means of a band or keeper 17, the latter being carried preferably by pivoting the same on a bolt 18 extending through the long shank 2 of the member 1. The band necessarily surrounds both the shank 2 and the arm 12.

Projecting laterally from corresponding sides of the free end of the shank 7 and the inner end of the shank 3 and having their flat sides disposed adjacent each other or in 110

abutting relation are semi-cylindrical lugs 19 and 20 respectively. The outer curved sides of the lugs 19 and 20 are provided with longitudinally extending teeth 21 which are 5 designed to bite into whatever is clamped by the wrench.

The above described wrench is particularly adapted for use in removing a short piece of pipe from a union, elbow or other 10 coupler, the elements 19 and 20 being inserted into the pipe and moved into gripping engagement with the interior wall of the same by pressing the lever arm 12 toward the long shank 2. This obviously swings 15 the lever so as to push upwardly on the nut 14 which is carried by the long shank 5 of the member 6 and this in turn moves said member so that the short shank 7 will move a slight distance away from the smaller 20 shank of the member 1. By turning the nut 14 the wrench may be adjusted to accommodate pipes of different sizes.

From the foregoing description taken in connection with the accompanying drawings 25 the construction, use and operation of the invention will be readily understood without a more extended explanation.

Various changes in form, proportion and 30 in the minor details of construction may be resorted to without departing from the spirit of the invention as defined in the appended claim.

What is claimed is:

A device of the class described comprising an L-shaped member having a long shank 35 serving as a handle and a short shank provided at its inner end with a jaw face adapted to engage the inner side of a pipe or the like and with an opening through its outer end, a second L-shaped member having a 40 threaded long shank extending through said opening and a short shank provided at its outer end with a jaw face adapted to engage the inner side of a pipe or the like and disposed opposite the jaw face carried by the 45 short shank of the first member, the corresponding shanks of said members being arranged in parallel relation and said short shanks projecting in opposite directions, an L-shaped lever having its short arm pivoted 50 to the long shank of the first member and provided with an opening through which the threaded long shank of the second member extends, the long arm of said lever being disposed alongside the long shank of the 55 first member to form a complementary handle, and a nut threaded upon the long shank of the second member and disposed between the short arm of said lever and the short shank of the first member.

In testimony whereof I have hereunto set my hand.

AUGUST MAGNAN.
